BROOM TENSIONING DEVICE

Filed March 23, 1931

UNITED STATES PATENT OFFICE

STEPHEN G. WILSON, OF PHILADELPHIA, PENNSYLVANIA

BROOM TENSIONING DEVICE

Application filed March 23, 1931. Serial No. 524,611.

The object of this invention is to devise a novel broom tensioning device which can be applied to any conventional construction of broom in order that the broom straws can be held in a more or less compact condition, and depending upon the adjustment of the tensioning device, the straws may be hard and stiff, or soft and flexible.

With the above in view my invention comprehends a novel broom tensioning device.

It further comprehends a novel broom tensioning device wherein a support or body portion is connected with the broom, and tensioning means surrounding the broom is adjustably carried by said support and locked with respect thereto.

Other novel features of construction and advantage will hereinafter more clearly appear in the detailed description and the appended claims.

For the purpose of illustrating the invention, I have shown in the accompanying drawings a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

Figure 1 is a side elevation of a portion of a broom in conjunction with which a broom tensioning device embodying my invention is employed.

Figure 2 is a perspective view of a detail of the body portion.

Figure 3 is an elevation on a reduced scale.

Figure 4 is a sectional view of a plate or strip and its fastening device.

Figure 5 is a rear elevation of a portion of the tensioning device.

Figure 6 is a perspective view of a portion of the support for the tensioning device.

Similar numerals of reference indicate corresponding parts.

Referring to the drawings:

1 designates a body portion or support which is made of sheet material and preferably of spring metal. The support 1 has

its marginal opposite edge portions inturned as at 2 and at the edges it is provided with the slits 3 which cause the support to be more flexible in one direction than in the other. The support 1 is secured to the broom by means of a strip 4, preferably of corrugated sheet metal, having the opposite marginal edges inturned as at 5 and depressed at its central portion as at 6 to receive the end of the pin 7 so that such end when pinched off will be flush with the outer face of the strip 4.

The pin 7 passes through a disc 8, the support 1, the broom straws, and through the strip 4. The disc and support are apertured as at 9 and 10 to receive the pin 7. In this manner, the body portion is securely fixed to the broom, preferably between the lines of sewing.

The support 1, near its upper end, is provided with outwardly extending portions which are inwardly deflected, as at 11, to form end members which can be pressed in between the broom straws. These end members are provided with deflected tongues 12 formed by pressing out portions of the metal so that they will form anchors to retain the end members within the broom straws. The end members of the support are thus securely fastened to the broom, preferably between the lines of stitching 13 which extend across the broom in the usual manner. The support 1 is provided with apertures 14 terminating at their lower ends in slots 15. These apertures and slots are longitudinally spaced from each other to provide for positioning the tensioning member 16 in such a position as to cause the broom straws to be soft, medium or hard.

The tensioning member 16 consists of a strand or strip of material, such as, for example, wire, having, in general, a rectangular contour, the free ends of the wire being connected with a carrier 17, portions of which are bent over the wire to form clasps 18. The lower portion of the carrier 17 is cut away to form an inwardly offset locking member 19 which depends downwardly and forms shoulders 20 against which the upwardly extending portions 21 of the wire contact. The portions 21, near their upper ends, pass through the aperture formed by the in-

wardly deflected portions 22 of the carrier 17 so that the outward movement away from each other of such portions 21 is limited but they can be moved towards each other by 5 the operator when desired.

To facilitate this operation, the upper portion of the carrier 17 is of reduced diameter, as at 23. The free ends of the upwardly extending portions 21 of the tensioning member 10 16 are bent rearwardly and laterally as at 24 to form hooks which can be passed through a selected aperture 14 and engage the rear walls surrounding such aperture to retain the carrier 17 in the position to which it has been 15 adjusted and to permit the rocking movement of the carrier when desired. At certain times the depending tongue 19 is locked in a slot 15, as will hereinafter be fully explained, to prevent such rocking movement of the carrier. 20

It will be understood from Figure 3 that the tensioning member 16 on one side of the broom is preferably lower than it is on the opposite side so that at the opposite edges 25 of the broom the wire inclines downwardly as at 25. This causes the straws at one face of the broom, for example, where the wire is lower, to be stiffer than the straws at the opposite face of the broom where the strand 30 of wire is higher.

The operation will now be apparent to those skilled in this art and is as follows:

Assuming first, that the user desires to have the broom straws soft, the free ends 24 of the 35 tensioning member formed by the wire are brought together and the locking ends 24 of the wire are inserted in the aperture 14 marked "soft", which brings the tensioning wire higher up making the straws below it 40 long and flexible. If it is desired that the broom straws be stiffer, the free ends are placed in the aperture 14 marked "medium", and if it is desired that the broom straws be 45 hard and less flexible, these free ends are placed in the aperture marked "hard". If only the free ends 24 are inserted into an aperture 14, the carrier 17 is pivotally connected with the body portion 1 so that the broom straws, although being held together 50 and made stiffer, yet they are free to move in an edgewise direction. If it is desired to increase the stiffness of the broom straws, in said direction, then, the depending tongue 19 is inserted in a selected slot 15 and the free 55 ends 24 are inserted into the juxtaposed aperture 14. In this case by edgewise movement of the broom, such as, for example, for scrubbing, the broom straws will be stiffer because the pivotal movement of the carrier 17 on the 60 body portion is prevented. The body portion at its upper end is fixedly anchored within the broom straws so that it will not swing sideways when an endwise movement of the broom is made, such as, for example, for 65 scrubbing or stiff sweeping.

If it is desired to sweep with the flat side or face of the broom in the usual manner, the broom straws will be softer when sweeping in one direction than they will be when sweeping in the opposite direction because the strand of wire on one side is lower than it is on the other. The body portion 1 also contributes to this action because the body portion 1 is more flexible in one direction than it is in the other. When the broom straws are flexing towards the support 1 the broom is softer than it is when the straws are flexing in the opposite direction, as the sections of the inturned opposite edges of the support 1 will abut and prevent its bending in that direction. 70 75 80

It will thus be apparent that I provide for having one side of the broom softer and more flexible than the opposite side of the broom and also for increasing or diminishing the tension on the broom straws by adjustment of the position of the carrier 17 on the body portion. I also provide for having the carrier 17 capable of a rocking movement on the body portion 1, or it can have a selected fixed portion on the body portion 1. The hard side of the broom is the face which carries the body portion 1. 85 90

Having thus described my invention what I claim as new and desire to secure by Letters Patent, is:— 95

1. In a broom tensioning device, a body portion, means to fasten the body portion to the broom, said body portion having openings longitudinally spaced from each other, 100 a carrier, and a wire surrounding the broom and connected with said carrier with its free ends laterally deflected and movably carried by said carrier whereby they can be brought together and passed through a selected opening to provide a pivotal movement therewith of the carrier. 105

2. In a broom tensioning device, a body portion, having opposite marginal portions inturned and provided with slits to permit flexibility in an outward direction, and having longitudinally spaced openings terminating in slots, said body portion having deflected upper ends to enter the broom straws, means to secure said body portion to a broom, 110 a carrier having a tongue to enter a selected slot in said body portion, and a wire tensioning member surrounding the broom and having its free ends movably carried by the carrier and terminating in laterally deflected locking members adapted to pass through a selected opening in said body portion. 115 120

3. In a broom tensioning device, a body portion, having opposite marginal portions inwardly deflected to enter the broom straws, longitudinally spaced openings, provided with deflected tongues, a disc on one side of the broom, a strip on the opposite side, a fastening device to secure said disc, strip and body portion to the broom, a carrier adapted 125 130

- to be locked in its longitudinally adjusted position on said body portion, and a wire tensioning member surrounding the broom, carried by said carrier, and adapted to engage 5 the walls of a selected opening of said body portion to retain the carrier and member in assembled relation therewith. 4. In a broom tensioning device, a body portion, having longitudinally spaced openings which terminate in slots, means to secure said body portion to the broom at its sewed portion, a tensioning member comprising a single strand of material surrounding the broom, and a carrier in which said strand 10 is slid able and provided with a tongue adapted to enter a selected slot and with shoulders which form fulcrums for the free end portions of the strand, the free ends of said strand having limited relative movement 15 on said carrier and terminating in laterally deflected locking elements adapted to pass through an opening in said carrier when brought together, and to engage the rear walls of a selected opening when released. 20 5. In a broom tensioning device, a body portion in the form of a longitudinally extending metal strip having longitudinally spaced openings terminating at one end in slots, means to secure said body portion at its 25 upper end to a broom, a carrier having means 30 to engage a selected slot, and a tensioning member in the form of a wire surrounding the broom and movably connected with said carrier with its free ends adapted to enter a selected opening and retain the carrier in as- 35 sembled relation therewith. 6. In a broom tensioning device, a corrugated strip of material to engage one side 40 of the broom, a longitudinally extending body portion to engage the opposite side of the broom, a disc on said body portion, a fastening device passing through said disc, body portion, the broom, and the strip, to secure the upper end of the body portion in 45 fixed relation with respect to the broom, said body portion being provided with longitudinally spaced openings terminating at their lower portions in slots, a carrier having means to engage said slots to engage a selected 50 slot, and a tensioning device in the form of a wire surrounding the broom straws and movably connected with said carrier with its free ends extending upwardly and terminating in deflected locking members, the tension inherent 55 in the wire tending to retain said locking members in locked engagement with the walls of an opening into which they have been inserted. 7. A broom tensioning device, comprising 60 a body portion in the form of a longitudinally extending strip having at its upper end deflected side portions provided with anchoring tongues to engage the broom straws, means to rigidly connect the upper part of 65 said body portion with the sewed portion of the broom, said body portion having openings longitudinally spaced relatively to the broom and terminating in slots, a carrier having a depending tongue to engage a selected slot and provided with shoulders in proximity to said tongue, and a wire tensioning member comprising a single strand of material having its ends connected with said carrier and provided with upwardly extending portions to fulcrum on said shoulders, said carrier having means to permit limited relative movement of the upper ends of said strand, said strand terminating in locking members adapted when brought together to pass through an opening and when released to interlock with the walls of an opening due to the tension of the strand. 70 8. In a broom tensioning device, a strip of material to engage one side of the broom, provided with a depressed portion which is apertured, a body portion to engage the opposite side of the broom, a disc engaging said body portion, a fastening device passing through said disc, said body portion, the broom, and the depressed seat of said strip, to rigidly connect the upper end of said body portion to the broom, said body portion being formed of spring metal and having opposite sides inturned and provided with slits to permit the body portion to bend more readily in one direction than in the other, a carrier longitudinally adjustable with respect to said body portion, and a tensioning member surrounding the broom and connected with said carrier. 85 9. A broom tensioning device, comprising a body portion in the form of a strip of spring metal, means to fixedly secure the upper end of said body portion to the broom at the portion where it is sewed, a carrier longitudinally adjustable on said body portion, said carrier and body portion having means common thereto to retain the carrier in adjusted position on the body portion, and a tensioning member surrounding the lower portion of the broom and having the portion extending across one face of the broom higher up on the broom than is the portion of said member on the opposite face of the broom. 90 100 STEPHEN G. WILSON. 115 105 110 120 125 130
